UNITED STATES PATENT OFFICE.

CLARENCE N. SCOTT, OF BUFFALO, NEW YORK, ASSIGNOR TO THE SNOW STEAM PUMP WORKS OF BUFFALO, OF SAME PLACE.

PUMPING-ENGINE.

SPECIFICATION forming part of Letters Patent No. 592,513, dated October 26, 1897.

Application filed January 12, 1897, Serial No. 618,948. (No model.)

To all whom it may concern:

Be it known that I, CLARENCE N. SCOTT, a subject of the Queen of Great Britain, residing at Buffalo, in the county of Erie and State of New York, have invented new and useful Improvements in Pumping-Engines, of which the following is a specification.

The object of this invention is to provide a pumping-engine with means whereby the stopping of the engine is prevented when the discharge of the pumped water or other liquid from the delivery stops temporarily. In pumping-engines which are used in connection with elevators it happens at times that no water is used and that consequently no water is discharged from the delivery-pipe of the pump, in which case the engine stops or becomes "stalled." In order to prevent this, I provide the delivery-pipe of the pump with an auxiliary escape or by-pass which is controlled by a speed-governor in such a way that when the speed of the engine has fallen to the lowest permissible or desirable point the by-pass is opened, allowing a sufficient escape of the pumped liquid to permit the engine to maintain this low speed, while when the normal discharge of the pumped liquid is resumed and the speed rises again the by-pass is closed.

In the accompanying drawings, consisting of two sheets, Figure 1 is a side elevation of a pumping-engine provided with my improvements. Fig. 2 is a sectional elevation, on an enlarged scale, of the by-pass valve and its automatic actuating mechanism. Fig. 3 is a top plan view of the same.

Like letters of reference refer to like parts in the several figures.

A represents the steam-cylinder, B the pump-cylinder, and C the fly-wheel shaft, of a pumping-engine which may be of any suitable construction and arrangement.

D represents the delivery-pipe, and d the suction-pipe.

e represents an auxiliary escape opening or by-pass formed in the delivery at a convenient point, and E represents the valve, which closes this by-pass in the normal operation of the pump. As shown in the drawings, this valve may be a double-beat or balanced valve

arranged in a casing F, provided with two valve-seats f f, which open into a discharge-pipe g, leading to the suction-pipe d or opening at some other convenient point.

H represents an actuating-cylinder containing a piston h, which is connected by a rod h' with the by-pass valve.

I represents a spring which bears against the piston h in the cylinder H and holds the valve closed. The tension of this spring can be adjusted by a screw i, arranged in the outer head i' of the cylinder. The cylinder H' is preferably supported by an open frame H', which is cast with the cylinder and the stuffing-box of the valve-casing.

J represents a pipe whereby the actuating fluid is supplied to the inner end of the cylinder, and j is a cock which is arranged in said pipe and which controls the flow of the liquid to the actuating-cylinder. The cylinder is provided at its inner end with a drain-opening k, through which the actuating fluid escapes from the cylinder. This opening is preferably made so small in area, as compared with the area of the supply-pipe, that no escape-valve is required. As actuating fluid I prefer to use the liquid in the delivery-pipe, and for that purpose the supply-pipe J is connected with the delivery-pipe, as shown.

L represents a centrifugal or speed governor which may be actuated from the engine-shaft by a belt l and pulleys l' l'', as shown. This governor is connected by a lever m and rod n with the arm on the plug of the supply-cock j in such manner that the supply-cock remains closed so long as the speed of the engine is greater than the lowest permissible or desirable speed, but is opened when the speed drops to the lowest speed at which the engine will maintain its motion. The lever m may be provided with a counter-balance m'.

So long as the engine runs at a speed which is higher than the lowest permissible or desirable speed the governor keeps the supply-cock j closed and the spring holds the by-pass valve closed, in which position of the valve its actuating-piston stands at the inner end of the cylinder. When the speed of the engine drops to the lowest permissible or de-

sirable point, the governor opens the supply-cock and the actuating fluid enters the inner end of the cylinder and forces the piston back against the pressure of the spring, thereby 5 opening the by-pass valve, which latter permits of a sufficient escape of liquid from the delivery to maintain this low speed of the engine. As soon as the speed of the engine increases by the escape of liquid from the de- 10 livery in the usual way the governor closes the supply-cock, shutting off the actuating fluid from the piston. The spring-pressure now forces the piston back as the fluid escapes from the cylinder through the small 15 escape-opening until the by-pass valve is closed.

I claim as my invention—

1. In a pumping-engine, the combination with the delivery having a by-pass and a valve 20 controlling said by-pass, of a cylinder and piston whereby said valve is actuated, and a speed-governor whereby the admission of the actuating fluid to said cylinder and piston is controlled in such manner that said valve is 25 opened when the speed falls to a certain point

and closed when the speed rises above such point, substantially as set forth.

2. In a pumping-engine, the combination with the delivery having a by-pass, of a valve controlling said by-pass, a valve-actuating piston and cylinder, a spring tending to seat 30 said valve, and a speed-governor whereby the supply of the actuating fluid to said cylinder is controlled, substantially as set forth.

3. In a pumping-engine, the combination 35 with the delivery having a by-pass, of a valve controlling said by-pass, an actuating-piston connected with said valve, a cylinder in which said piston is arranged, a spring bearing against said piston and tending to seat said 40 valve, a conduit for actuating fluid opening into the cylinder and provided with a cock, and a speed-governor connected with said cock, substantially as set forth.

Witness my hand this 9th day of January, 45 1897.

CLARENCE N. SCOTT.
